(57) **CLAIM**

The ornamental design for a cosmetic container, as shown and described.

DESCRIPTION

FIG. 1 is a top, front, and left side perspective view of a cosmetic container showing our new design;

FIG. 2 is a top plan view thereof;

FIG. 3 is a left side elevation view; with right side elevation view thereof being identical;

FIG. 4 is a bottom plan view thereof;

FIG. 5 is a front elevation view thereof; and,

FIG. 6 is a rear elevation view thereof.

Broken line portions of the cosmetic container shown in the figures are for illustrative purposes only and form no part of the claimed design.

1 Claim, 4 Drawing Sheets
